(57) **CLAIM**

The ornamental design for a hang tag, as shown and described.

DESCRIPTION

FIG. 1 is front perspective view of the hang tag.

FIG. 2 is a front side elevational view of the hang tag, the right side elevational view being a mirror image thereof.

FIG. 3 is a front elevational view of the hang tag.

FIG. 4 is a top plan view of the hang tag.

FIG. 5 is a bottom plan view of the hang tag; and,

FIG. 6 is a back elevational view of the hang tag.

The broken lines in FIGS. 1–6 are for illustrative purposes only, and form no part of the claimed design.
